United States Patent Office

Des. 181,513
Patented Nov. 26, 1957

181,513

LUGGAGE RACK POST OR SIMILAR ARTICLE

Kenneth W. Binding, Winchester, Mass., assignor to Market Forge Company, Everett, Mass., a corporation of Massachusetts

Application January 22, 1957, Serial No. 44,557

Term of patent 14 years

(Cl. D14—27)

Fig. 1

Fig. 4

Fig. 2

Fig. 3

Fig. 5

Fig. 1 is a plan view of a luggage rack post or similar article showing my new design;

Fig. 2 is a side elevational view;

Fig. 3 is an elevation viewed in the direction of the arrows 3—3 of Fig. 2;

Fig. 4 is an elevation viewed in the direction of the arrows 4—4 of Fig. 1; and

Fig. 5 is a bottom view.

I claim:

The ornamental design for a luggage rack post or similar article, substantially as shown.
